(57) CLAIM

The ornamental design for a hand bag, as shown and described.

DESCRIPTION

FIG. 1 is a top perspective view of a hand bag, showing our new design;

FIG. 2 is a bottom perspective thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and

FIG. 8 is a bottom plan view thereof.

FIG. 9 is a top perspective view of another embodiment of the hand bag;

FIG. 10 is a bottom perspective thereof;

FIG. 11 is a front view thereof;

FIG. 12 is a rear view thereof;

FIG. 13 is a left side view thereof;

FIG. 14 is a right side view thereof;

FIG. 15 is a top plan view thereof; and,

FIG. 16 is a bottom plan view thereof.

The dashed lines in the drawings depict portions of the design that form no part of the claim.
